US00D821112S

(12) **United States Design Patent** (10) **Patent No.:** **US D821,112 S**
(45) **Date of Patent:** **** Jun. 26, 2018**

(54) **CONTAINER**

(71) Applicant: **Johnson & Johnson Consumer Inc.**,
Skillman, NJ (US)

(72) Inventors: **Michael Cannamela**, Atlantic Highlands, NJ (US); **Evan Rhodes**, Brooklyn, NY (US); **Max Knecht**, Brooklyn, NY (US); **Anthony B. Gallo, Jr.**, Warren, NJ (US); **Aimee Sealfon**, Brooklyn, NY (US); **Ernesto Quinteros**, South Orange, NJ (US); **Timothy O'Toole**, Jersey City, NJ (US); **Raffaele Mazzei**, Montclair, NJ (US); **Melissa Dandy**, Hillsborough, NJ (US); **Sabrina Adami**, Hard (AT); **Stephane Robic**, Val de Reuil (FR); **Fabrizio Camplone**, Pescara (IT); **Simone Nenning**, Hard (AT)

(73) Assignee: **Johnson & Johnson Consumer Inc.**,
Skillman, NJ (US)

(**) Term: **15 Years**

(21) Appl. No.: **29/583,225**

(22) Filed: **Nov. 3, 2016**

Related U.S. Application Data

(63) Continuation-in-part of application No. 29/564,562, filed on May 13, 2016.

CLAIM

The ornamental design for a container, as shown and described.

DESCRIPTION

FIG. 1 is a top perspective view of the back side of a container showing our new design.

FIG. 2 is a bottom perspective view of the front side thereof.

FIG. 3 is a front elevational view thereof.

FIG. 4 is a right side elevational view thereof.

FIG. 5 is a rear elevational view thereof.

FIG. 6 is a left side elevational view thereof.

FIG. 7 is a top plan view thereof; and,

FIG. 8 is a bottom plan view thereof.

The ornamental design which is claimed is shown in solid lines in the drawings.

1 Claim, 6 Drawing Sheets
